THREE WHEELED COMPACT AUTOMOBILE

Glenn R. Thomas, 2116 NW. 23rd St., and Charles E. Kerr, 1449½ NW. 30th St., both of Oklahoma City, Okla.

Filed Apr. 20, 1964, Ser. No. 79,567

Term of patent 14 years

(Cl. D14—3)

FIG. 1

FIG. 2

FIG. 3

FIGURE 1 is a perspective view of the three wheeled compact automobile as it appears when viewed from above the left front end of the automobile showing our new design.

FIGURE 2 is a view in elevation of the three wheeled compact automobile as it appears when viewed from the front end thereof.

FIGURE 3 is a view in elevation of the three wheeled compact automobile as it appears when viewed from the rear end thereof.

FIGURE 4 is a view in elevation of the three wheeled compact automobile as it appears when viewed from the left side thereof.

FIGURE 5 is a plan view of the three wheeled compact automobile as it appears when viewed from above.

We claim:

The ornamental design for a three wheeled compact automobile, as shown.
